CLOCK

Walter B. Herbst, Evanston, and Ralph M. La Zar, Skokie, Ill., assignors to Sunbeam Corporation, Chicago, Ill.

Filed July 6, 1971, Ser. No. 159,605

Term of patent 14 years

Int. Cl. D10—01
U.S. Cl. D42—7

FIG. 1 is a front elevational view of a clock showing our new design;

FIG. 2 is a top plan view thereof; and

FIG. 3 is a right side elevational view of FIG. 1, the left side being a mirror image thereof.

We claim:

The ornamental design for a clock, as shown.
